UNITED STATES PATENT OFFICE.

JULIAN G. GOODHUE, OF CHICAGO, ILLINOIS.

ATOMIZER.

1,329,833.

Specification of Letters Patent.

Patented Feb. 3, 1920.

Original application filed May 13, 1912, Serial No. 696,901. Divided and this application filed February 7, 1913, Serial No. 746,740. Renewed June 21, 1919. Serial No. 305,911.

To all whom it may concern:

Be it known that I, JULIAN G. GOODHUE, a citizen of the United States, residing at Chicago, in the county of Cook and State of Illinois, have invented a certain new and useful Improvement in Atomizers, of which the following is a full, clear, concise, and exact description, reference being had to the accompanying drawings, forming a part of this specification.

My invention relates to an improved form of atomizer and has as its principal object the provision of an atomizer which shall be efficient in its action and at the same time shall be manufactured as cheaply as possible and installed with a minimum of labor when it is found that a connection leading from a rear instead of a side wall is necessary, as a device of this character is usually introduced into the bowl from a side thereof. This would necessarily require that the atomizer extend laterally from a member leading from the rear wall.

A further object of my invention resides in the particular arrangement and combination of parts hereinafter described.

Referring to the accompanying drawings, Figure 1 is a perspective view of my improved atomizer, the lower part being broken away;

Fig. 2 is an inverted plan view of the top piece of my atomizer;

Fig. 3 is a vertical section on the line 3—3 of Fig. 1;

Fig. 4 is a vertical section on the line 4—4 of Fig. 1, showing certain additional parts for supporting the atomizer, not shown in Fig. 1.

Referring more particularly to the drawings, 1 is a top piece or cap member which is provided with a central horizontal section 2. At one end of the section 2 is a cylindrical hub 3 integral therewith. Projecting from the hub 3 in a direction at right angles to the part 2 is a semi-tubular wedge 4. As shown in Figs. 1 and 2, the part 3 is closed on one side by a face 5, in which is an aperture 6.

At the end of the part 2 opposite the hub 3 is a top piece 7 also projecting at right angles to the direction of the part 2. Part 7 is provided with a cap 8 at one end. Opposite the piece 7 the part 2 carries a hook shaped lug 9. Immediately below the part 7 are suspended two similar castings 10 and

11, made right and left respectively. Each of the parts 10 and 11 comprises a vertical portion 12 and a horizontal portion 13. The parts 12 are semi-cylindrical, as indicated in Fig. 3 and inclose the inner tube 14, preferably of glass, for holding the liquid to be sprayed by the atomizer. Each of the castings 10 and 11 is provided with ears or lugs 15—15, situated at the top of the vertical portions 12, while at the end of each of the horizontal portions 13 is a lug 16 which projects within the cap 8. Now when the lugs 16 are placed within the cap and a screw 17 passed through the lugs 15 above the horizontal portion of the lug 9, it will be seen that the parts 10 and 11 will be firmly held in place by the use of only one screw, and also that the device can be readily assembled.

As shown in Fig. 3 certain tubes are necessary for the operation of my atomizer. Tube 18 delivers liquid into the receptacle 14 and is preferably connected with some exterior reservoir for maintaining a constant liquid level in 14. The tube 19 delivers air for causing the spray, and is preferably connected to a door check. The tube 19 is provided with an aperture 20, through which the air blast is delivered. The tube 21 leads from the bottom of the receptacle 14 to a point near the aperture 20. As plainly shown, the aperture 20 is designed to direct a blast of air across the open end of the tube 21, thus sucking liquid from the receptacle 14 and spraying it into the air. Since the aperture 20 faces downwardly, each of the parts 13 is provided with a cut-away portion 22 forming an opening for the delivery of the spray. As shown in Fig. 2 all of the parts of the member 1 are hollowed out forming a semi-cylindrical groove for the accommodation of the tubes 18 and 19. Also the part 7 and each of the parts 13 are provided with recesses for the reception of a cylindrical block 23. It will be understood that the block 23 is drilled to permit the passage of the tubes 19 and 21, and is designed to hold these tubes securely in place.

Applicant's method of supporting his atomizer is illustrated in Fig. 4, in which 24 is a tubular conduit or pipe used for inclosing the small tubes 18 and 19, and also for supporting the atomizer. To attach the atomizer to the pipe 24 I make use of a wedge member 25 which co-operates with the wedge shaped part 4. The member 25 is

attached to a screw 26 which passes through the aperture 6. At first the screw 26 is inserted into the part 25 only a short distance, the parts 4 and 25 are placed with inclined edges in engagement, and the parts 4 and 25 are then inserted into the open end of the conduit 24. The screw 26 is then tightened, whereupon the parts 4 and 25 are wedged firmly against the inner face of the conduit 24 supporting the atomizer firmly in position.

This application is a division of my application, Serial No. 696,901, filed May 13, 1912, Disinfecting Apparatus.

Having thus described my invention, what I claim is:

1. An atomizer structure comprising a supporting cap piece, said piece having a central channelled semi-cylindrical part and having at one end of said part a hollow cylindrical hub, a securing member attached to said hub at one side and a plate closing the end of said hub on its face opposite said securing member, said plate being provided with an aperture through which a member adapted to coöperate with the securing member is adapted to be inserted.

2. In an atomizer, a supporting member comprising a body portion, an end portion having an open side, said end portion having its respective ends provided with a recessed

portion and a hook whereby atomizer instrumentalities may be secured to said end portion, and a shank extending laterally from one end of the body portion.

3. In an atomizer, a supporting member for supporting the atomizer instrumentalities, said supporting member having a body portion and a pair of laterally extending members projecting from said body portion, one of said laterally extending members forming a means by which the supporting member is mounted and the other of said laterally extending members having its respective ends provided with a recessed portion and a hooked end portion forming a means for supporting the atomizer instrumentalities.

4. In an atomizer, a supporting member having a body portion, laterally extending members extending from said body portion, one of said lateral extensions being open at one side to permit the introduction of atomizing instrumentalities and the other laterally extending member forming a means of support for the body portion.

In witness whereof, I hereunto subscribe my name this 24th day of June, A. D., 1912.

JULIAN G. GOODHUE.
